JOHN JOSLYN, OF CANTON, NEW YORK.

Letters Patent No. 62,208, dated February 19, 1867.

IMPROVED CRIMPING MACHINE.

The Schedule referred to in these Letters Patent and making part of the same.

TO ALL WHOM IT MAY CONCERN:

TO ALL WHOM IT MAY CONCERN:
Be it known that I, JOHN JOSLYN, of Canton, in the county of St. Lawrence, and State of New York, have invented a new and useful improvement in Boot-Crimping Machines; and I do hereby declare that the following is a full, clear, and exact description thereof, which will enable others skilled in the art to make and use the same, reference being had to the accompanying drawings, forming part of this specification.

same, reference being had to the accompanying drawings, forming part of this specification.

By the machine embraced in the present invention, the leather which is to be crimped is drawn between two similar plates, having a series of circular depressions or cavities, or their equivalents, in their opposite and parallel faces or sides, and in contact with the leather, by means of a suitable shaped former so arranged as to move between the said plates; the circular depressions working the leather, and producing that condensing of such portions of the same as are necessarily fulled, as well as materially aiding in the fulling process, and causing such a hold to be had upon the leather, as it is drawn between them, as to force or stretch it out to the utmost extent.

I will now proceed

Having thus in general terms premised the principal feature of the present invention, I will now proceed to describe the same in detail, reference being had to the accompanying plate of drawings, in which—

Figure 1 is a plan or top view of the machine.

Figure 2, a rear elevation; and

Figure 3 a transverse vertical section, taken in the plane of the line x x , fig. 1.

Similar letters of reference indicate like parts.

Figure 3 a transverse vertical view. Similar letters of reference indicate like parts. A A, in the drawings, represent the framework of the machine, which consists of parallel uprights, B B, secured at their lower ends in feet C, and connected together at suitable points of their lengths by cross-bars D D. Upon the upper cross-bars D D two similar plates E E are placed, parallel to each other, with their faces or surfaces opposite each other, made with a series of similar semicircular depressions or cavities F F arranged in parallel rows, and extending in a vertical direction at an angle of forty-five degrees, (45°), or nearly so, to that of the plates, from the upper end toward the lower end, or that resting upon the cross-bars D D, where they terminate in semicircular shaped grooves or channels G G extending in the same direction with the circular cavities. The upper ends of the plates E are made of an angular shape, with the apex of the angle at a point nearly half way between the two sides of the plates. H H, two gates, hung at one end I upon each side of the upper part of the framework A so as to swing thereon, which gates extend across the said framework back of the plates E. At their ends J is a screw-shaft, K, passing freely through them and freely through the framework, with a suitable shaped head, L, upon one end for convenience in turning it so as to press the gates H H upon the plates E. On each gate H, half way between its two ends, or nearly so, is a vertical cross-bar, M, having in both ends set screws N, which, by screwing in, are made to move the two plates E E toward each other, and thus decrease the space or opening between them, and for the purpose of giving a proper bearing to the gate H upon the plates E. Between the two uprights B, extending entirely across from one to the other, is arranged a frame, P, having a form, P², at its upper end made of the angular shape shown in the drawings, and its two side pieces Q Q, each made with a toothed rack, R, with which engage the pinion-wheels S S of a transverse horizontal shaft, T, turning in suitable bearings of the uprights B. U, a gear-wheel on outer end of shaft T, and V another but smaller gear-wheel having crank-handle W for turning it, and engaging with the said gear-wheel U, so that if the crank-handle W be turned, the frame P will be either raised or lowered, as the case may be, moving in and between the cross-bars D D of the uprights B B, and the plates E resting upon such cross-bars D D; friction-rollers X X being provided at suitable points of the uprights B B, bearing against the frame P, to keep it in position as it is moved up and down, as explained.

upon such cross-bars D, friction being provided to hold the leather against the frame P, to keep it in position as it is moved up and down, as explained. In the use of the machine above described, the leather which is to be crimped is properly laid over and across the upper ends of the two plates E E, the form having been first lifted above the same, and the plates E adjusted to the proper distance apart by means of the set-screws N, when, turning the crank-handle W in the proper direction, the form is made to move or travel downward, drawing the leather with it, down and between the two plates E E, thereby crimping the same, the circular cavities or depressions working the leather and producing a condensing of its particles where most needed in those parts necessarily fulled, while at the same time they materially aid the fulling process and hold the leather, causing it to be drawn out to its utmost extent.

by the form as it moves down between the plates E. It is self-evident that the outer part of a circle impressed and moving over a pliable surface would have the effect to spread the material, and that the inner part would have the effect to contract or condense it, but as these cavities have no outer circular form, their action must be to contract or condense the material drawn over them; and furthermore, not only do these cavities have the effect to contract or condense the leather, but also to force it toward the angle of the form, from the fact that the edge of the form comes in contact with them at an angle of forty-five degrees (45°) or thereabouts, allowing the lower half of these cavities to move along this edge a distance about equal to their diameters, and, gradually closing in upon the leather, compress it in its proper place, as is plainly apparent from an inspection of fig. 2 in the drawings; the grooves at the bottom of the plate, or the ribs produced by them, having the tendency to spread the leather out at the points where needed after the crimping has been done as above explained, thereby perfectly crimping a boot, which it is only necessary, then, to place upon a suitable form to dry; the leather, by continuing the downward movement of the form sufficiently therefor, being completely drawn out from and between the plates, thereby removing all imprints. By passing the leather over the entire length of the corrugated plates E, as hereinabove explained, the perfect crimping of it is obtained, for if the surfaces of the plates were smooth no great advantage would be secured by passing the leather through them, as is obvious without further explanation. The pressure upon the leather being crimped may be regulated at pleasure by simply adjusting the screw-shaft K according to the pressure desired, and to suit the thickness of the leather. The various parts composing my improved machine may be made of any materials which are suitable, and therefore I do not intend to limit myself to any one particular material of which they are made, nor to any particular form of cavities or depressions in the plates E E, as they can be varied in many respects, and yet the same result, as hereinabove stated, be accomplished.

What I claim as new, and desire to secure by Letters Patent, is—

Crimping boots by passing or drawing the leather down and between two stationary or fixed plates, having their surfaces opposite to each other, or with which the leather comes in contact, corrugated or formed with a series of circular or other suitable shaped cavities or depressions, substantially as herein described.

I also claim so arranging the corrugated plates E E, or their equivalents, that they can be adjusted to any degree of pressure upon the leather being crimped, substantially as and for the purpose described.

JOHN JOSLYN.
